UNITED STATES PATENT OFFICE

GEORGE H. GILMAN, OF CLAREMONT, NEW HAMPSHIRE, ASSIGNOR TO SULLIVAN MACHINERY COMPANY, A CORPORATION OF MASSACHUSETTS

HOISTING MECHANISM

Application filed October 22, 1919, Serial No. 332,519. Renewed October 16, 1929.

My invention relates to hoisting mechanisms.

It has for its object to provide an improved pressure fluid actuated hoisting mechanism and one which is powerful in operation and compact in form. A further object of my invention is to provide an improved hoisting mechanism having an improved pressure fluid motor of the combined motor and speed reduction type which is adapted to be reversed and to enable reductions of widely varying degree to be obtained as desired. A still further object of my invention is to provide an improved and simplified pressure fluid actuated hoisting mechanism which is light, compact, and rugged, and adapted to use in varied relations as a winding drum or hoist, the same, however, being especially adapted to use as a mine hoist. These and other objects and advantages of my improved construction will, however, herein-after more fully appear.

In the accompanying drawings I have shown for purposes of illustration one form which my invention may assume in practice, illustrating the same as applied to a winding drum or hoist such as a mine hoist.

In these drawings,—

Fig. 1 is a side elevation of a hoist embodying my invention, certain parts being broken away or sectioned to facilitate illustration.

Fig. 2 is a longitudinal vertical sectional view of the construction shown in Fig. 1.

Fig. 3 is a transverse sectional view on line 3—3 of Fig. 2, illustrating one set of rotors.

Fig. 4 is a similar view on line 4—4 of Fig. 2, illustrating the other set of rotors.

Fig. 5 is a longitudinal sectional view on line 5—5 of Fig. 3, illustrating one set of pressure fluid connections.

Fig. 6 is a similar view on line 6—6 of Fig. 4, illustrating another set of the same.

Fig. 7 is a sectional view on line 7—7 of Fig. 2, showing certain of the throttle valve passages.

Fig. 8 is a sectional view on line 8—8 of Fig. 2, showing other valve passages.

Fig. 9 is a sectional view similar to Figs.

7 and 8, showing the throttle valve in neutral position.

In this illustrative construction I have shown a winding drum 1, journaled on suitable bearings 2. This drum is rotatable about a central shaft 3 which is in turn carried in suitable bearings 4, the parts being held in assembled relation by a clamping bolt 5 threaded into one end of the shaft at 6. The bearings 4 are carried by suitable arms 7 formed on any suitable support 8, herein in the form of a trunnion adapted to be adjustably mounted and clamped as desired on a bar or otherwise, in the same general manner as a rock drill.

Disposed within the drum 1 and operatively connected thereto in an improved manner, is my improved motor. The same is herein shown as enclosed within a suitable casing 9 arranged coaxially with the shaft 3 and rotatable relative thereto on suitable bearings 10 disposed at opposite ends of the casing. As shown, this casing houses a plurality of sets of rotors, one set being rotatable about a fixed gear and carrying with it the other set of rotors, which themselves rotate at a materially reduced speed a rotatable gear connected to the drum. Accordingly the construction is such that each set of rotors cooperates with the other, not only in the rotation of the drum but in producing the speed reduction desired.

Referring more particularly to the drawings, Figs. 2 to 4, it will be noted that a fixed gear 11 is disposed within one end of the casing 9 and suitably keyed to the shaft 3, as at 12. A plurality of smaller gears or rotors 13 having a smaller number of teeth than the gear 11 are arranged about the gear 11 in mesh with the same, the rotors 13 being snugly housed in suitable bosses on the casing 9. Each rotor 13 is herein suitably splined, as at 14, to a suitable shaft 15 disposed longitudinally of the casing and journaled therein in suitable bearings 16 at opposite ends of the casing. Here, attention is also directed to the fact that the shafts 15 are provided at points substantially midway between their ends with spacing flanges 17; and that the same carry on the opposite side 101

of the flanges 17 from the gears 13, another set of rotor gears 18 having a larger number of teeth than the gears 13, and similarly splined, at 19, to the shafts. These gears 18 in turn mesh with an axially located rotatable gear 20 having a larger number of teeth than the gears 11, 13, and 18. The gear 20 is keyed, as at 21, to a sleeve shaft 22 rotatable on the shaft 3 and herein formed integral with an end member 23 of the drum 1, which end member is normally rigidly connected to the drum by screws 24.

We will next consider the motive fluid connections to the rotors. Here, it will be noted that pressure fluid, preferably laden with lubricant, is supplied to the device from a suitable line 25 through a throttle valve 26. This valve 26 is in turn controlled by a usual control handle 27; and herein has a central chamber 28 adapted to supply motive fluid from the line alternatively through either of superimposed ports 29 to the corresponding passages 30 or 31 disposed longitudinally of the shaft 3. The valve is also provided with a pair of superimposed peripheral passages or ports 32 adapted alternatively to establish communication between the passages 30 or 31 and a downwardly disposed exhaust port or passage 33 formed in the valve casing. Thus it will also be noted that the valve is made reversible and adapted, when its handle is in the position A illustrated in Figs. 7 and 8 to supply fluid to the passage 30 and receive exhaust from the passage 31, while when in its position B illustrated in those figures, it is adapted to supply fluid to the passage 31 and receive exhaust from the passage 30, neither passage receiving motive fluid when the valve is in its intermediate or neutral position C illustrated. We will first consider the pressure fluid connections when fluid is supplied through the passage 30. Here, it will be observed (Figs. 5 and 6) that the fluid entering through the passage 30 passes out through ports 35 communicating with the passage 30, into an annular passage 36 formed in one of the bearings 10 of the casing 9, and that from this annular passage the pressure fluid is supplied through ports or passages 37 to longitudinally disposed passages 38. These passages 38 are formed in those portions of the casing 9 which are adjacent the teeth of the gears 11 and 20. As the sets of rotors 13, 18, are both mounted on the shafts 15, each passage 38 is extended beside both a rotor 13 and a rotor 18, and is adapted to supply motive fluid through distributing ports 39 thereto at a plurality of points along their length and substantially opposite their line of mesh with their cooperating stationary and rotatable gears 11 and 20, respectively. As shown, the exhaust from the thus rotated gears 13, 18 passes out of the casing 9 through exhaust ports 40 opening into the drum interior, which in turn communicates with the

atmosphere through exhaust ports 41 formed in the drum end 23. Here it will also be noted that the exhaust from the gears 11 and 20 passes out through ports and passages 42, 43, corresponding to the ports and passages 39, 38, and oppositely located with respect thereto; the passages 43 communicating through passages 44 with annular passages 45 formed in the other casing bearing 10, which annular passages in turn communicate through ports 46 and 47 formed in the sleeve 22 and shaft 3, respectively, with a longitudinally disposed exhaust passage 48 which opens into the exhaust passage 31. Conversely, when the throttle valve is thrown into its reversing position, it will be evident that motive fluid will be supplied through the passages 43 and ports 42 and exhausted through the ports 39 and passages 38, while when the valve is in its neutral position (Fig. 9) no air will flow to the motor.

In the operation of my improved construction, it will be observed that, when motive fluid is admitted through the passages 38 and ports 39 or through the passages 43 and ports 42, the gears 13 will be caused to rotate about their axes and bodily about the fixed gear 11, thereby producing a rotation of the casing 9. At the same time it will be noted that air is also admitted through the ports 39 to the gears 18. These gears, as they thus bodily rotate with the casing, are also caused to rotate about their own axes; and due to the difference in the number of teeth on the various gears the rotatable gear 20 and the connected drum 1 are driven in a direction opposite to the direction of rotation of the casing and at a materially reduced speed. The reduction in speed is dependent upon the number of teeth employed in the different sets of gears and the arrangement of the gears. For example, it has been found possible in my present construction, by merely varying the gears, i.e. using gears having different numbers of teeth, to produce twelve different speeds and a reduction varying from 10 to 1 to 174 to 1, while utilizing the same casing; and it will, of course, be understood that by the use of casings of different sizes even further variations may be obtained within the same drum. Here attention is also directed to the fact that it has been discovered that by interchanging the sets of gears, as, for instance, by interchanging gear 11 with gear 20 and the gears 13 with gears 18, it is possible to obtain a reversal of rotation. It has also been found that by simply throwing the control handle 27 into its neutral position it is possible to lock the drum in any desired position, this arising from the fact that the reduction is so great that the reduction mechanism acts substantially as does a worm and worm gear; to lock the parts in any desired position. Due to this self-locking feature there is no necessity for the use of additional braking mechanism.

As a result of my improved construction wherein the entire mechanism is carried within the drum, it will be observed that a very light, powerful, and compact mechanism is produced, and one which, while adapted to use in other relations, is especially adapted to use as a winding drum or hoist. More specifically, it has been found that through my improved construction it has 10 been possible to reduce by substantially fifty per cent, the weight of a winding mechanism of a given capacity, thereby enabling the mechanism to be used with far greater facility and to be handled and used in various 15 relations where the weight of such mechanisms has heretofore made it impossible to use them. Attention is also directed to the fact that in my improved construction, wherein it is possible to vary the number of 20 speeds obtainable, I am thereby enabled to meet various conditions encountered in practice, with great facility. These and other advantages of my improved construction will, however, be clearly apparent to those 25 skilled in the art.

While I have in this application specifically described one form which my invention may assume in practice, it will be understood that this form is shown for illustrative purposes and that the invention may be modified and embodied in various other forms without departing from its spirit or the scope of the appended claims.

What I claim as new and desire to secure 35 by Letters Patent is:

1. In a hoist, a shaft, a winding drum rotatably mounted thereon, a reversible pressure fluid motor comprising compound motor and reduction gearing carried on said 40 shaft and housed within said drum, means for supplying pressure fluid to said motor to act on the teeth of said motor and reduction gearing, means for exhausting fluid from said motor, said supply and exhaust 45 means including passages disposed within said shaft substantially axially of said drum, means for reversing said motor and drum including a reversible controlling valve carried at one end of said shaft, means for holding one of said gears against rotation, and means connecting another of said gears in operative driving relation with said drum.

2. In a hoist, a central stationary shaft, a winding drum rotatably mounted thereon, a bearing member carried by said drum, a pressure fluid motor housed within said drum and comprising motor and reduction gearing carried on said shaft, said motor having a casing journaled at one end on said bearing member and at the other end journaled on said shaft, means for supplying pressure fluid to said motor to act on the teeth of said motor and reduction gearing, means for exhausting fluid from said motor, said supply and exhaust means including

longitudinally disposed supply and exhaust passages formed in said shaft, supplemental exhaust means for said motor in said drum, means for securing one of said gears to said shaft, and means connecting another of said gears in operative driving relation with said drum. 70

3. In a hoist, a winding drum, a pressure fluid motor housed within said drum and comprising motor and reduction gearing, a sleeve connected to one of the gear elements thereof, a shaft extending through said motor and sleeve, said drum being journaled on said shaft, means for supplying pressure fluid to said motor to act on the teeth of said motor and reduction gearing, means for exhausting fluid from said motor, and means connecting said sleeve to said drum. 75

4. In a hoist, spaced supporting standards, a stationary shaft connected to each of the same, a winding drum rotatably mounted on said shaft, an annular bearing member rigidly connected thereto and disposed concentrically with said shaft, a gear secured to said bearing member, and driving means for said drum carried by said shaft including reduction gearing meshing with said first mentioned gear and supporting means for said reduction gearing rotatably mounted on said bearing member. 85

5. In a hoist, spaced supporting standards, a stationary shaft connected thereto, a winding drum disposed between said standards and rotatably mounted on said shaft, said drum having a sleeve member rigidly connected thereto and disposed about said shaft, and gearing for driving said drum disposed within the drum and including a gear supported on said sleeve, a second gear disposed coaxially therewith, and a train of gearing connecting said coaxially disposed gears. 95

6. In a hoist, a winding drum, means for supporting said drum comprising a shaft having a passage formed therein, a pressure fluid motor disposed within said drum comprising intermeshing motor gears, means including said shaft for supplying pressure fluid to act on the teeth of said motor gears, means for exhausting fluid from said motor, means for holding one of said motor gears against rotation, means forming a part of said motor for rotatably supporting the remaining gears, and means including transmission gearing connecting another of said motor gears in operative driving relation with said drum, one of said transmission gears being directly connected to said latter motor gears so as to be rotated directly thereby and also rotatable relative to said motor gear supporting means. 110

7. In a hoist, a stationary shaft, a winding drum rotatably mounted on said shaft, a pressure fluid motor disposed within said drum comprising intermeshing motor gears, one of said gears being fixed against rotation relative to said shaft, means forming a part of 125

said motor for rotatably supporting the remaining gears, means for supplying pressure fluid to act on the teeth of said motor gears, means for exhausting fluid from said motor, and means including transmission gearing connecting another than the fixed gear of said motor gears in operative driving relation with said drum, one of said transmission gears being directly connected to said latter motor gears so as to be rotated directly thereby and also rotatable relative to said motor gear supporting means.

8. In a hoist, a winding drum, means for supporting said drum comprising a shaft having a passage formed therein, a pressure fluid motor disposed within said drum comprising intermeshing motor gears, means for supporting certain of said gears for rotation on axes offset from and disposed on opposite sides of a plane including the drum axis, means including said shaft for supplying pressure fluid to act on the teeth of said motor gears, means for exhausting fluid from said motor, means for holding one of said motor gears against rotation relative to said shaft, and means including transmission gearing for connecting another of said latter motor gears in operative driving relation with said drum, one of said transmission gears being directly connected to said latter motor gears so as to be rotated directly thereby and also rotatable relative to said motor gear supporting means.

9. In a hoist, a winding drum, means for supporting said drum comprising a shaft having a passage formed therein, a pressure fluid motor disposed within said drum comprising intermeshing motor gears, means for supporting certain of said gears for rotation on axes offset from and disposed on opposite sides of a plane including the drum axis, the axes of said latter motor gears sweeping through surfaces of revolution as said drum rotates, means including said shaft for supplying pressure fluid to act on the teeth of said motor gears, means for exhausting fluid from said motor, means for holding one of said motor gears against rotation relative to said shaft, and means including transmission gearing for connecting another of said latter motor gears in operative driving relation with said drum, one of said transmission gears being directly connected to said latter motor gears so as to be rotated directly thereby and also rotatable relative to said motor gear supporting means.

10. In a hoist, a winding drum, means for supporting said drum comprising a shaft having a passage formed therein, a pressure fluid motor disposed within said drum comprising intermeshing motor gears, means for supporting certain of said gears for rotation on axes offset from and disposed on opposite sides of a plane including the drum axis, the axes of said latter motor gears sweeping through surfaces of revolution in a direction

opposite from the direction of drum rotation as said drum rotates, means including said shaft for supplying pressure fluid to act on the teeth of said motor gears, means for exhausting fluid from said motor, means for holding one of said motor gears against rotation relative to said shaft, and means including transmission gearing for connecting another of said latter motor gears in operative driving relation with said drum, one of said transmission gears being directly connected to said latter motor gears so as to be rotated directly thereby and also rotatable relative to said motor gear supporting means.

11. In a hoist, a winding drum, a pressure fluid motor disposed within said drum comprising intermeshing motor gears a plurality of which are arranged coaxially with the drum axis, means for supplying pressure fluid to said motor to act on the teeth of said motor gears, means for exhausting fluid from said motor, and means for holding one of said coaxial motor gears against rotation, another of said coaxial motor gears being fixed against rotation relative to said winding drum.

12. In a hoist, a winding drum, means for supporting said drum comprising a shaft having a passage formed therein, a pressure fluid motor disposed within said drum comprising intermeshing motor gears, means for supporting certain of said gears rotating on axes offset from and disposed on opposite sides of a plane including the drum axis, the axes of said latter motor gears sweeping through surfaces of revolution as said drum rotates, means including said shaft for supplying pressure fluid to said motor to act on the teeth of said motor gears, means for exhausting fluid from said motor, and means including transmission gearing for connecting one of said offset motor gears in operative driving relation with said drum, one of said transmission gears being directly connected to said latter motor gears so as to be rotated directly thereby and also rotatable relative to said motor gear supporting means.

13. In a hoist, a winding drum, means for supporting said drum comprising a shaft having a passage formed therein, a pressure fluid motor disposed within said drum comprising intermeshing motor gears, means for supporting certain of said gears rotating on axes offset from and disposed on opposite sides of a plane including the drum axis, the axes of said latter motor gears sweeping through surfaces of revolution in a direction opposite to the direction of drum rotation as said drum rotates, means including said shaft for supplying pressure fluid to said motor to act on the teeth of said motor gears, means for exhausting fluid from said motor, and means including transmission gearing for connecting one of said offset motor gears in operative driving relation with said drum,

one of said transmission gears being directly connected to said latter motor gears so as to be rotated directly thereby and also rotatable relative to said motor gear supporting means.

5 14. In a hoist, a winding drum, means for supporting said drum comprising a shaft having a passage formed therein, a pressure fluid motor comprising compound motor and reduction gearing carried on said shaft and housed within said drum, means including said shaft for supplying pressure fluid to said motor to act on the teeth of said motor and reduction gearing, means for exhausting fluid from said motor, means for holding 10 one of said gears against rotation, and means connecting another of said gears in operative driving relation with said drum.

15 15. In a hoist, a winding drum, means for supporting said drum comprising a shaft 20 having a passage formed therein, a pressure fluid motor comprising compound planetary motor and reduction gearing carried on said shaft and housed within said drum, means including said shaft for supplying pressure fluid to said motor to act on the teeth of said motor and reduction gearing, means for exhausting fluid from said motor, means for holding one of said gears against rotation, and means connecting another of said gears 25 in operative driving relation with said drum.

30 16. In a hoist, a winding drum, means for supporting said drum comprising a shaft having a passage formed therein, a pressure fluid motor housed within said drum and comprising motor and reduction gearing, an operative driving connection between said motor and drum comprising a sleeve extending within said motor, a gear of said gearing being secured to said sleeve, means including 35 said shaft for supplying pressure fluid to said motor to act on the teeth of said motor and reduction gearing, and means for exhausting fluid from said motor.

40 17. In a hoist, a winding drum, a pressure fluid motor housed within said drum comprising motor and reduction gearing including coaxially arranged gears, a shaft supported for orbital movement about said coaxially arranged gears, and other gears meshing with said coaxially arranged gears and secured to said shaft, means for supplying pressure fluid to said motor to act on the teeth of all of said gears, means for exhausting fluid from said motor, and means connecting 50 said gearing to said drum.

55 18. In a hoist, a winding drum, means for supporting said drum comprising a shaft having a passage formed therein, a pressure fluid motor housed within said drum and comprising a casing and motor and reduction gearing disposed within said casing, said casing being rotatable relative to said drum, means including said shaft for supplying pressure fluid to said motor to act on the teeth 60 of said motor and reduction gearing, means

for exhausting fluid from said motor, and means connecting said gearing to said drum.

70 19. In a hoist, a winding drum, a pressure fluid motor housed within said drum comprising motor and reduction gearing including coaxially arranged gears, a shaft supported for orbital movement about said coaxially arranged gears, and other gears meshing with said coaxially arranged gears and secured to said shaft, means for supplying pressure fluid to said motor to act on the teeth of said gears, means for exhausting fluid from said motor, means for holding one of said coaxial motor gears against rotation, and means connecting another of said coaxial motor gears in driving relation with said drum.

75 20. In a hoist, a winding drum, means for supporting said drum comprising a shaft having a passage formed therein, a pressure fluid motor housed within said drum and comprising a casing supported for rotation relative to said drum, and motor and reduction gearing disposed within said casing, said gearing including gears arranged coaxially with said casing, and other gears meshing with said coaxial gears and rotatably mounted in said casing, means including said shaft for supplying pressure fluid to said motor to act on the teeth of said motor and reduction gearing, means for exhausting fluid from said motor, means for holding one of said coaxial gears against rotation, and means connecting another of said coaxial gears in driving relation with said drum.

80 21. In a hoist, a winding drum, a pressure fluid motor disposed within said drum comprising intermeshing motor gears, operative driving connections between said motor and drum including a shaft disposed coaxially with said drum, a gear secured to said shaft and driven by said motor and disposed within said motor and a gear meshing with said latter gear and also disposed within said motor.

85 22. In a hoist, a winding drum, means for supporting said drum comprising a shaft having a passage formed therein, a pressure fluid motor disposed within said drum comprising a motor casing arranged coaxially with said drum and rotatable relative thereto, and a plurality of intermeshing fluid pressure operated motor gears arranged within said casing, means including said shaft for supplying pressure fluid to said motor to act on the teeth of said motor gears, means for exhausting fluid from said motor, and means for connecting said motor in operative driving relation with said drum comprising a second shaft mounted for rotation relative to said motor casing and projecting within the same and having a gear carried thereby and disposed within said motor casing for effecting drum rotation.

90 23. In a hoist, a winding drum, means for supporting said drum comprising a shaft

- having a passage formed therein, a pressure fluid motor disposed within said drum comprising a motor casing and a plurality of intermeshing fluid pressure operated motor gears arranged within said casing, means including said shaft for supplying pressure fluid to said motor to act on the teeth of said motor gears, means for exhausting fluid from said motor, and means for connecting said motor in operative driving relation with said drum comprising a second shaft mounted for rotation relative to said motor casing and projecting within the same and carrying a reduction gear.
24. In a hoist, a winding drum, means for supporting said drum comprising a shaft having a passage formed therein, a pressure fluid motor disposed within said drum comprising a motor casing arranged coaxially with said drum and rotatable relative thereto, and a plurality of intermeshing fluid pressure operated motor gears arranged within said casing, means including said shaft for supplying pressure fluid to said motor to act on the teeth of said motor gears, means for exhausting fluid from said motor, and means for connecting said motor in operative driving relation with said drum comprising a second shaft secured to said drum and carrying one of said motor gears.
25. In a hoist, a winding drum, means for supporting said drum comprising a stationary shaft, a motor housed within said drum, said motor comprising a casing rotatable relative to said shaft, and motor and reduction gear rotors disposed in said casing, said motor and reduction gear rotors constituting epicyclic gearing, one of said gear rotors being fixed against rotation relative to said shaft, and a member connecting said motor in driving relation with said drum, said member being rotated by said epicyclic gearing in the opposite direction from said casing.
26. In a hoist, a winding drum, means for supporting said drum comprising an element extending within the same, a motor disposed within said drum having a casing rotatable relative to said drum, and means for connecting said motor in operative driving relation with said drum comprising a member secured to said drum and projecting into said motor, said casing being supported at one end on said element and at the other end on said member.
27. In a hoist, a winding drum, means for supporting said drum comprising a shaft extending through the same, a motor disposed within said drum having a casing rotatable relative to said drum, and means for connecting said motor in operative driving relation with said drum comprising a sleeve surrounding said shaft and secured to said drum, said casing being supported at one end on said shaft and at the other end on said sleeve.
28. In a hoist, a winding drum, a pressure fluid motor disposed within said drum, means for supporting said drum and motor comprising a shaft having a passage formed therein, said motor comprising intermeshing gear rotors, certain of said gear rotors rotating on axes offset from and disposed on opposite sides of a plane including the drum axis, means including said shaft for supplying pressure fluid to act on the teeth of said gear rotors, means for exhausting fluid from said motor, and means for producing rotation of said drum by said motor including a sleeve coaxial with said drum and having fixed thereto at its inner end a gear driven by said motor.
29. In a hoist, a winding drum, and means for rotating the same comprising a motor casing disposed within said drum and rotatable relative thereto on the axis thereof, intermeshing motor gears disposed within said casing, certain of said gears rotating on axes offset from and disposed on opposite sides of a plane including the drum axis, means for supporting said motor casing comprising a shaft having a passage therein for supplying pressure fluid to act on the teeth of said motor gears, a shaft carrying one of said latter motor gears and secured thereto, a second gear secured to said shaft; and a sleeve coaxial with said drum and having fixed thereto at its inner end a gear driven by said last mentioned gear.
30. In a hoist, a winding drum, and means for rotating the same comprising a pressure fluid motor disposed within said drum, a motor driven shaft coaxial with said drum disposed at one end of said motor, a stationary conduit element coaxial with said drum, said element being formed with supply and exhaust passages, and a valve for controlling said passages, said valve being adapted to reverse said motor by interchanging the connections to exhaust and supply, said motor comprising a central motor gear, a shaft parallel thereto and having fixed thereto a motor gear meshing with said central motor gear, another gear secured to said parallel shaft, and a gear meshing therewith and secured to said driven shaft.
- In testimony whereof I affix my signature.
GEORGE H. GILMAN.
